UNITED STATES PATENT OFFICE

2,537,749

SLIDER FOR SEPARABLE FASTENERS

Richard G. Gloss, Cranston, R. I.

Application January 11, 1946, Serial No. 640,415

1 Claim. (Cl. 24—205.14)

1

This invention relates to a slider for separable fasteners and more particularly to the pull tab secured to such slider. It is usual in separable fasteners to provide some separate piece extending from the top wall of the slider which is provided with openings for the reception of portions of the pull tab or a pin to connect the pull tab thereto. This requires separate parts and the handling of several pieces of material in assembly. The pull tab in some cases carries a locking projection and in such cases the locking projection is usually formed from the pull tab by bending a part of the pull tab into position. The bend strains the stock and provides an inherent weakness where the locking projection is so bent.

One of the objects of this invention is to provide a means for attaching a pull tab to a slider without the use of a separate pin or any separate parts.

Another object of this invention is to simplify the construction of a pull tab and slider and the assembly of these parts.

Another object of this invention is to so manipulate the stock of the slider that the pull tab cannot be disengaged from the slider.

Another object of this invention is to provide stronger pivot means than where such pivot means are carried by the pull tab.

Another object of this invention is to provide a camming locking action which will be stronger than where projections are bent from the pull tab.

With these and other objects in view, the invention consists of certain novel features of construction, as will be more fully described and particularly pointed out in the appended claims.

In the accompanying drawings:

Fig. 1 is a top plan view of the slider with the pull tab attached;

Fig. 2 is a sectional view illustrating only the upper wall of the slider with the pull tab attached thereto;

Fig. 3 is a view similar to Fig. 2 but on a section taken at right angles thereto;

Fig. 4 is a view similar to Fig. 3, illustrating the pull tab in a different relative position to the slider;

Fig. 5 is a perspective view of the pull tab;

Fig. 6 is a perspective view of the blank showing the pull tab as cut from sheet stock and before being bent into position.

In proceeding with this invention, I cut spaced slots in the upper wall of the slider and raise the strip between these slots which is provided

with trunnions so that these trunnions are readily accessible. I then bend a pull tab from a cut-out blank having openings in it and mount these openings on the trunnions and then depress the strip so that the ends of the pull tab move into the slots in the slider and are there locked in position by the edges of the slots.

With reference to the drawings, 10 designates generally the slider and 11 generally the pull tab. The slider has spaced walls, the upper of which is designated 15 and is provided with spaced slots 14, 14 leaving a strip 12 between these slots with slits 16 and 17, 18 and 19 extending beyond the slots and into top wall 15. In cutting out the slots 14, the strip 12 is left with trunnions 13 extending laterally therefrom in opposite directions providing a pivot. This strip 12 may be raised from the general plane of the wall 15 as illustrated in Fig. 4 so as to provide access to the trunnions 13.

The tab 11 is cut out from sheet stock as illustrated in Fig. 6 and provided with enlarged circular ends 20 each having openings 21. The tab may be bent as at 22, 23 so as to form the same generally U-shape with the upper surface 24 of the tab being substantially in a single plane while the thickness of this bent stock, shown in Fig. 3, 5, and 6 is greater than the thickness of the sheet stock in the general plane of the pull tab. This U-shape formation provides the openings 21 so that they may be bent toward each other onto the raised trunnions 13 and then the tab will be set in this position. After which the strip 12 may be depressed so that these enlarged portions 20 will move into the slots 14 as shown in Figs. 2 and 3 so that the pull tab is locked in position.

In order that the pull tab may serve as a lock for locking the slider to the fasteners, cam portions 25 and 26 are provided extending from the enlarged portion 20 so that as the pull tab is moved from a position such as shown in Fig. 4 to a position such as shown in Fig. 3 these cam portions will engage the fasteners and hold the slider against movement.

A stop is provided on the bridge portion of the tab to limit its pivotal movement into locked position.

I claim:

A slider for separable fasteners comprising a top wall with its upper surface in substantially a single plane and having spaced slots through the top wall with a strip between, pivot trunnions formed of the same piece of material as said strip and extending in opposite directions

into said slots, a generally U-shaped pull tab with its ends located in said slots and provided with pivot openings receiving said trunnions, said trunnions being partly below the upper surface of said top wall to lock the pull tab in said slots. 5
